Primary Examiner — Marianne N Pandozzi*Assistant Examiner* — Jae Liang(74) *Attorney, Agent, or Firm* — Tucker Ellis LLP(57) **CLAIM**

The ornamental design for a cocktail shaker with reamer, as shown and described.

DESCRIPTION

FIG. 1 is a perspective view of a cocktail shaker with reamer;

FIG. 2 is a top view of a cocktail shaker with reamer;

FIG. 3 is a front-side view of a cocktail shaker with reamer;

FIG. 4 is a bottom view of a cocktail shaker with reamer;

FIG. 5 is a back view of a cocktail shaker with reamer; and,

FIG. 6 is an exploded view of a cocktail shaker with reamer. The broken lines are shown for the purpose of illustrating parts of the cocktail shaker with reamer that form no part of the claimed design.

1 Claim, 6 Drawing Sheets(56)
